UNITED STATES PATENT OFFICE.

JOHN H. VINTON, OF KEENE, NEW HAMPSHIRE, ASSIGNOR TO BAXTER D. WHITNEY & SON, INC., OF WINCHENDON, MASSACHUSETTS, A CORPORATION OF MASSACHUSETTS.

HEEL-TURNING-MACHINE BLOCK-HOLDER.

1,397,844.

Specification of Letters Patent.

Patented Nov. 22, 1921.

Application filed May 20, 1920. Serial No. 382,848.

To all whom it may concern:

Be it known that I, JOHN H. VINTON, a citizen of the United States, residing at Keene, in the county of Cheshire and State 5 of New Hampshire, have invented new and useful Improvements in Heel-Turning-Machine Block-Holders, of which the following is a specification.

This invention relates to an improvement 10 in heel turning machine block holders.

The object of the invention is to provide a holder for blocks of wood out of which heels are to be made by shaping said blocks of wood by means of vertical rotary cutters, 15 the holder being positioned upon a swinging arm and pivoted thereon so that in conjunction with certain cam-shaped tracks and formers the block may be positioned relatively to a pair of rotary cutters so as to 20 form a block to the shape of a heel first on one side of said block coöperating with one cutter and second on the opposite side of the block coöperating with another cutter, the block when finally shaped as set forth forming 25 a wooden heel for boots or shoes.

It is very essential in machines of this character that the block should be very firmly held in position in every direction while the cutting operation is taking place 30 and it is one of the objects of this invention to provide a holder for the block which so positions and holds the same that heels produced by the machine will be correctly formed and will be duplicates.

In machines of this character it is desirable and in fact essential that heels of different sizes, shapes and heights may be 35 formed thereon and it is one of the objects of this invention to provide a holder for the block which can be adjusted and adapted to clamp blocks of different heights firmly in position and furthermore to provide a device on which heels of different shapes and thicknesses may be formed.

It has been found in machines of this character that there is a tendency for the cutter to lift the block holder during the cutting operation and thus make defective heels and it is one of the objects of this 40 invention to overcome that difficulty.

It is furthermore the object of the invention to provide a block holder of the character set forth which may be readily and

accurately adjusted and held in adjusted position, to secure the objects hereinbefore 55 set forth.

To these ends the invention consists in the combination and arrangement of parts set forth in the following specification and particularly pointed out in the claims 60 thereof.

Referring to the drawings:

Figure 1 is a side elevation partly in section of my improved block holder showing the same positioned upon a portion of a 65 heel turning machine.

Fig. 2 is a detail sectional elevation taken on the line 2—2, Fig. 1.

Fig. 3 is a detail sectional elevation taken 70 on the line 3—3, Fig. 1.

Fig. 4 is a detail side elevation of the primary frame.

Fig. 5 is a plan view of my improved block holder showing the same in connection with a portion of a heel turning machine. 75

Fig. 6 is a plan view of the block holder plate.

Figs. 7 to 12 inclusive are diagrammatic plan views illustrating the different positions which are assumed by the block holder 80 and its former relatively to the cutter.

Like numerals refer to like parts throughout the several views of the drawings.

In the drawings, 15 is the frame of the heel turning machine, 16 and 17 are the 85 cutters which are fast to vertical rotary shafts 18 and 19 respectively, said shafts being rotatably mounted in bearings on the frame of the machine. 20 is a vertical shaft upon which is mounted an arm 21. 90 The arm 21 is provided with bearings 22 and 23 in which is slidably and rotatably mounted a shaft 24. The shaft 24 has a collar 25 fastened thereto and between this collar and the lower end of the bearing 22 said shaft 24 is encircled by a spring 26, the tendency of said spring being to hold the shaft 24 downwardly. To the lower end of the shaft 24 is fastened an arm 27 and journaled to said arm is a long roll 28 which is adapted, when the machine is in operation, to engage a cam shaft track 29. When the machine is not in operation then said cam shaft track will engage a flat surface 30 upon the under side of said 105 arm 27.

The upper end of the shaft 24 has a former 31 fastened thereto which in the operation of the machine is adapted to engage guides 32 and 33, as hereinafter described. A frame-holder 34 is also fastened to the upper end of the shaft 24 and is slotted at 35 to receive a portion of a primary frame 36 which projects into said slot and is pivoted to the frame-holder 34 at 37. A screw 38 projects through the frame-holder 34 and through the slot 35 and also projects through a slot 39 provided in the frame 36 and has screw-threaded engagement with the frame-holder 34 on one side of said slot 35 so that by tightening up the screw 38 any wear which may take place between the frame 36 and the opposite sides of the slot 35 in the holder 34 will be taken up so that the frame 36 may always have a suitably snug fit in the slot 35. A block of wood 42 rests upon a support 43 which is fastened to and forms in effect a portion of the primary frame 36. A gage 44 is adjustably fastened by means of a screw 45 to the primary frame 36.

The block 42 is clamped against the support 43 by a primary clamping member 46, said primary clamping member being pivotally mounted upon a pin 47 which is supported in a standard 48 forming a portion of an auxiliary frame 49. The auxiliary frame 49 is slidably mounted transversely of the shaft 24 upon ways 50 provided upon the primary frame 36 and is held in adjusted position by set screws 51. The primary clamping member 46 is bifurcated to allow the auxiliary frame 49 to project upwardly therethrough, and upon the upper end of said auxiliary frame a secondary clamping member 53 is pivoted at 54. An adjusting screw 55 has screw-threaded engagement with the front end of said secondary clamping member and the lower end thereof rests against the upper edge of the primary clamping member 46 at its forward end. The screw 55 is locked in adjusted position by a set nut 56. A toggle lever 57 is pivoted at 58 to the rear end of the secondary clamping member 53. Said toggle lever is provided with a handle 59. A pair of links 60 are mounted upon the pin 47 at their lower ends and at their upper ends are connected to the toggle lever 57 by a pin 61. When the toggle lever 57 and the links 60 are in the position illustrated in full lines, Fig. 1, then the secondary clamping member is in position to force the primary clamping member downwardly at its forward end, and by so doing to force a jaw 62 which is attached to said primary clamping member against the block 42 and thus to clamp said block between the jaw 62 and the support 43. When the toggle lever 57 is moved to the position illustrated in dotted lines, Fig. 1, the links 60 and the secondary clamping

member assume the positions illustrated in dotted lines in said figure, and the primary clamping member 46 is raised to the position illustrated in dotted lines by a flat spring 63 which, at its rear end, is fastened to the auxiliary frame 49, and at its front end bears against the under side of the primary clamping member 46. When the toggle lever is moved to its lowered position indicated in full lines Fig. 1, it is stopped from further movement in the same direction by a stop screw 64 which is fastened to the arm 48 of the auxiliary frame 49, and when in this position the pivots of the links and of the toggle lever are in alinement so that the greatest power of the toggle consisting of the toggle lever and the toggle links is then in effect and the block is clamped in position between the jaw 62 and the support 43 and the parts are then locked in clamping position. The frame 36 is provided with a roll 65 which is journaled upon a bracket 66 fast to the underside of the auxiliary frame 49 and said bracket is extended downwardly at 67 to form an arm which is adapted to engage a stop or projection 68 fastened to a cam shaft track 69 which in turn is supported upon the frame 15 of the machine and is engaged by the roll 65. Both the track 29 and the track 69 may be adjusted upwardly and downwardly by means of adjusting screws 70 and 71 respectively, which adjusting screws have screw-threaded engagement with brackets 72 and 73 fast to the frame 15 of the machine.

It is very essential in the operation of the machine that the block of wood which is shaped by cutters to make a heel should be at all times held firmly in position in every direction and also that it should be positioned so that the center line of the heel when completed will coincide with the center line of the shaft 24 and to accomplish this for different sizes of heels the gage 44 is adjusted so that independent of the size of the heel the block will be so positioned that in the finished heel the center line will coincide with the center line of the shaft 24.

It is also very essential that different heights of heels may be clamped in the same holder and to do this different jaws 62 are provided, also in different heels there is a variation in the inclination of the tread of the heel or of the upper and lower surfaces of the block from which the heel is to be made and this variation is compensated for by tipping the jaw 62 upon its pivot 74, otherwise if the jaw 62 were rigidly fastened to the primary clamping member 46 the block would be tipped upon its support 43 and thus lead to imperfect work.

It is also desirable that in a device of this character the primary clamping member, the secondary clamping member and the toggle device should be adjustable simultaneously

in order that the forward end of the primary clamping member and its jaw 62 may be positioned to suit varying shapes and sizes of heels, and this is accomplished in this 5 embodiment of my invention by adjusting the auxiliary frame 49 together with its arm 48 forwardly or backwardly upon the ways 50 and then clamping the auxiliary frame to the ways 50 by means of the set screws 51.

10 It will be seen that the support 43 being fastened to the frame 36 by a screw 43', different supports may be attached to said frame, of different contours, lengths and widths and also of different thicknesses as 15 may be desired to accommodate different shapes, sizes or heights of blocks and heels which are formed from said blocks.

10 It will be understood that the primary frame 36 and the auxiliary frame 49 form 20 together in effect a single frame and in some of the claims the word "frame" is used with this meaning.

10 The general operation of the mechanism hereinbefore specifically described is as follows: A block of wood is placed upon the support 43 with the front edge of the block corresponding to the breast of the finished heel abutting against the gage 44. At this time the handle 59 of the toggle lever 57 will 25 be in its raised or dotted position, Fig. 1. The clamping member 53 and the links will also be in the dotted positions shown in Fig. 1 and the primary clamping member will be raised to the dotted position illustrated in 30 Fig. 1 by the spring 63. The block having been placed in position, the handle 59 is now pushed downwardly from the dotted position to the full position illustrated in Fig. 1, thus causing the toggle links and their pivots 35 and the pivot of the toggle lever to be brought into alignment with each other and causing the secondary clamping member 53 through the screw 55 to force the primary clamping member and its jaw 62 downwardly, thus firmly clamping the block 42 40 in position against its holder 43. At this time the longitudinal median plane B—B, Fig. 7, of the holder coincides with the longitudinal median plane A—A of the 45 arm 21.

50 The operator moves the holder and the parts supported thereon until the center lines A—A and B—B of the arm and holder respectively assume the relative positions 55 illustrated in Fig. 8 with the former 31 in engagement with the guide 32 and with one side of the block in engagement with the cutter 16, the operator then turns the holder and its supporting arm counter-clockwise 60 the block being held in engagement with the cutter 16 until the parts arrive in the position illustrated in Fig. 9. During these motions the former 31 is held against the guide 65 32 and the frame 36 is raised and lowered by means of the shaft 24, arm 27 and track

29 and is tipped upon its pivot 37 by means of the roll 65 and cam shaped track 69 in order to produce the proper shaped contour for the heel of the shoe on one side of the heel from the breast to the middle of the 70 back of said heel, all in a manner well known to those skilled in this art.

75 The operator having finished one side of the heel now moves the parts to the position illustrated in Fig. 10 which is the same as the position illustrated in Fig. 7 and then moves the parts until their center lines A—A and B—B assume the positions illustrated in Fig. 11 and finally to the positions illustrated in Fig. 12, thus completing the forming of the heel of the shoe.

80 The parts are then moved back to the position illustrated in Fig. 7 and the toggle lever 57 is thrown into the position illustrated in dotted lines, Fig. 1, thus releasing the heel of the shoe and allowing it to be removed by the operator from the holder.

I claim:

1. A heel turning machine block holder having, in combination, a support for a 90 block, a primary clamping member adapted to engage said block, a pivot for said primary clamping member, and a lever constituting a secondary clamping member and adapted to engage said primary clamping 95 member and cause the same to engage said block and force it against said support, and a toggle device connected to said secondary clamping member and adapted to cause the same to engage said primary clamping member and lock said primary and said secondary clamping members in position with said block clamped against said support.

100 2. A heel turning machine block holder having, in combination, a support for a block, a frame constituting a portion thereof, a frame-holder upon which said frame is pivoted, a primary clamping member pivoted to said frame, a lever constituting a secondary clamping member pivoted to said frame, a toggle lever pivoted to said secondary clamping member and a toggle link connecting said toggle lever to said frame whereby said secondary clamping member may be caused to engage said primary 115 clamping member and cooperate with the same to force said block against said support.

120 3. A heel turning machine block holder having, in combination, a support for a block, a frame constituting a portion thereof, a frame-holder upon which said frame is pivoted, a primary clamping member pivoted to said frame, a lever constituting a secondary clamping member pivoted to said frame, and a toggle lever and link pivoted to each other, one of said toggle members being pivotally connected to said secondary clamping member and the other to said frame whereby said secondary clamping 125 member

member may be caused to coöperate with said primary clamping member to force said block against said support.

4. A heel turning machine block holder having, in combination, a support for a block, a frame constituting a portion thereof, a frame-holder upon which said frame is pivoted, a primary clamping member pivoted to said frame, a lever constituting a secondary clamping member pivoted to said frame, a toggle lever and link pivoted to each other, one of said toggle members being pivotally connected to said secondary clamping member and the other to said frame whereby said secondary clamping member may be caused to coöperate with said primary clamping member to force said block against said support, and means to limit the distance to which said toggle lever

20 can be rocked in one direction.

5. A heel turning machine block holder having, in combination, a support for a block, a primary frame constituting a portion thereof, a frame holder upon which said primary frame is pivoted, a vertical shaft constituting a pivot for said frame holder, an auxiliary frame slidable upon said primary frame transversely of said vertical shaft, a primary clamping member pivoted 25 on said auxiliary frame, a secondary clamping member pivoted on said auxiliary frame and adapted to coöperate with said primary clamping member to cause it to engage said block and clamp said block to said support, 30 and a toggle device adapted to lock said secondary clamping member in position with said primary clamping member forcing said block against said support.

6. A heel turning machine block holder having, in combination, a support for a block, a primary frame constituting a portion thereof, a frame holder upon which said primary frame is pivoted, a vertical shaft constituting a pivot for said frame holder, an auxiliary frame slidable upon said frame transversely of said vertical shaft, a primary clamping member pivoted on said auxiliary frame, a secondary clamping member pivoted on said auxiliary frame 45 and adapted to coöperate with said primary clamping member to cause it to engage said block and clamp said block to said support, a toggle lever pivoted to said secondary clamping member, and a toggle link pivoted 50 to said auxiliary frame and pivotally connected to said toggle lever whereby said secondary clamping member may be caused to engage said primary clamping member to force said block against said support and 55 lock said clamping members in position.

7. A heel turning machine block holder having, in combination, a support for a block, a frame constituting a portion of said support, a primary clamping member piv-

oted to said frame and adapted to engage 65 said block, a lever constituting a secondary clamping member pivoted to said frame and adapted to engage said primary clamping member, a toggle device adapted to lock said primary and secondary clamping members 70 in position with said block clamped against said support, a roll journaled upon said frame and extending transversely of said shaft and a cam shaped track upon which said roll is adapted to travel whereby a 75 rocking motion may be imparted to said frame.

8. A heel turning machine block holder having, in combination, a support for a block, a frame constituting a portion thereof, a frame holder upon which said frame is pivoted, a vertical rock shaft to which said frame holder is fastened, a primary clamping member pivoted to said frame and adapted to engage said block, a lever constituting 80 a secondary clamping member pivoted to said frame and adapted to engage said primary clamping member, a toggle device adapted to lock said primary and secondary clamping members in position with said 85 block clamped against said support, a roll journaled upon said frame and extending transversely of said rock shaft, a cam shaped track upon which said roll is adapted to travel whereby a rocking motion may 90 be imparted to said frame, an arm fastened to said rock shaft, a roll journaled upon said arm and extending transversely of said rock shaft and a second cam shaped track adapted to be engaged by said last mentioned roll whereby a vertical movement 95 may be imparted to said block holder.

9. A heel turning machine block holder having, in combination, a support for a block, a frame constituting a portion thereof, a frame holder upon which said frame is pivoted, a vertical rock shaft to which said frame holder is fastened, means mounted upon said frame adapted to clamp a block against said holder, a roll journaled upon 105 said frame and extending transversely of said rock shaft, a cam-shaped track upon which said roll is adapted to travel, an arm fastened to said rock shaft, a roll journaled upon said arm and extending transversely 110 of said rock shaft, a second cam-shaped track adapted to be engaged by said last-mentioned roll, and a spring acting to move said rock shaft downwardly, whereby said rolls may be held in engagement with their 115 respective tracks and a combined vertical and rocking motion imparted to said frame.

In testimony whereof I have hereunto set my hand in presence of a subscribing witness.

JOHN H. VINTON.

Witness:

FRANKLIN E. LOW.
